(57) **CLAIM**

The ornamental design for a jewelry ring clamp with round wedge, as shown and described.

DESCRIPTION

FIG. 1 is a front perspective view of the jewelry ring clamp with round wedge;

FIG. 2 is a front elevational view of the jewelry ring clamp with round wedge of FIG. 1;

FIG. 3 is a rear elevational view of the jewelry ring clamp with round wedge of FIG. 1;

FIG. 4 is a top plan view of the jewelry ring clamp with round wedge of FIG. 1;

FIG. 5 is a bottom plan view of the jewelry ring clamp with round wedge of FIG. 1;

FIG. 6 is a right side elevational view of the jewelry ring clamp with round wedge of FIG. 1;

FIG. 7 is a left side elevational view of the jewelry ring clamp with round wedge of FIG. 1; and,

FIG. 8 is a front perspective view of the jewelry ring clamp with round wedge of FIG. 1 with the round wedge portion removed for ease of disclosure.

The broken lines depict portions of the article that form no part of the claimed design.

1 Claim, 4 Drawing Sheets
